UNITED STATES PATENT OFFICE.

CHARLES P. EVANS, OF MILTON, MASSACHUSETTS.

CLASP.

1,023,559.

Specification of Letters Patent.

Patented Apr. 16, 1912.

Application filed January 19, 1909. Serial No. 473,054.

To all whom it may concern:

Be it known that I, CHARLES P. EVANS, a citizen of the United States, residing at Milton, in the county of Norfolk and State 5 of Massachusetts, have invented certain new and useful Improvements in Clasps, of which the following is a specification.

This invention relates to clasps, and it relates particularly to that class of those 10 articles of which an example is shown in the United States Patent No. 785,720, dated March 28th, 1905.

In the production of the clasps of the character shown in the patent referred to, 15 it is essential that the smallest possible quantity of metal be employed in order that the article may be sufficiently cheap, light and flexible, and at the same time it is necessary that the clasp shall be rigid at 20 the point where a fabric is engaged and shall be of such form that the retaining parts shall be capable of uniformly contacting throughout a considerable length with the fabric so engaged.

25 The object which I have in view is to overcome the defects of the clasp shown in the patent referred to and of others of the class, and with this object in view the invention consists of the clasp having the generic and specific features substantially as hereinafter described and claimed.

In the accompanying drawings I have illustrated several forms of embodiment of the invention.

35 In these drawings, Figure 1 is a representation of the blank from which one form of the clasp is made; Fig. 2 is a view showing the outer face of the clasp; Fig. 3 is a view showing the inner face of the clasp; Fig. 4 is a transverse sectional view, the section being taken on line 4-4 of Fig. 2; Fig. 5 is a view of a modified form of fastener adapted for securing the flap of an envelop; Fig. 6 is a modified form adapted 40 for use on the retaining band of an umbrella; and, Fig. 7 is a view showing a modified form of fastener adapted for use as a bundle fastener or for a like purpose.

50 The clasp in the first form illustrated in the drawing is of spring metal and is hook-shaped in general contour. In this form the fastener has a main portion or body 1 provided in the upper end thereof with an elongated opening 2 furnishing means for 55 attaching it to a garter or the like in con-

nnection with which it is to be used. The lower end of the body of the blank has projecting therefrom the narrow flexible extension 3, with which is formed the arm 4 which extends substantially parallel to the body 1 and is separated therefrom by a slot 5. The edge of the body 1 forming one side of the slot 5 has an upturned edge 6 which serves both to strengthen and stiffen the body at this point where most strain 65 is imposed upon it in use, and also to adapt it to coact with a locking flange by which a fabric engaged by the clasp is confined.

The arm 4, as shown particularly in Fig. 2, tapers from its point of juncture with the connection 3 toward its end, thus giving the slot 5 between the arm and the body a taper form. The arm is concavo-convex in cross section providing a rigid support for the locking flange 7, which is formed with it, 75 and presents a convex exposed inner face which is incapable of engaging or injuring articles with which it contacts.

The flange 7 is formed with the arm 4, and in shaping the blank is bent back upon 80 such arm to extend over the outer face of the arm and also over the slot 5. The inner edge of the flange overlaps the upturned edge of the body 1. The entire outer edge of the flange is connected with the edge of 85 the arm 4 and is as strong and rigid as the thickness of the metal of which the clasp permits, and there is a tendency to maintain the inner edge of the flange parallel with the upturned edge 6 at all times, thus insuring 90 the grasping of a fabric interposed between the parts throughout the length of the flange.

The connection 3 is slightly offset from the body 1 so that the arm 4 extends in a different plane from the body, thus bringing the inner face of the locking flange 7 which is as described joined to the connection by the arm, in the same plane as the face of the upturned edge of the body 1. The upper 100 edge 8 of the flange is preferably inclined downward from its outer to its inner edge presenting a V-shaped opening between such upper end and the body of the clasp.

The form of fastener hereinbefore described is adapted particularly for use as a hose supporter, but the essential features of the device may by slight modification of structure be advantageously used for other purposes. For instance as shown in Fig. 5 110

of the drawing the fastener may be formed with a short body 9 having projecting therefrom prongs 10 adapting it for attachment to paper or cloth and may be used with advantage as means for securing the flap of an envelop.

In the form shown in Fig. 6 the body 9 of the fastener has an extension 11, provided with an opening 12 for the reception 10 of thread by which it may be secured in place for use upon an umbrella to secure the free end of a retaining band.

In another modified form, shown in Fig. 7, each end of the body may be provided 15 with the securing means herein described, adapting it for use as a bundle tie or for a similar use.

In the use of the clasp a fabric to be engaged and retained is presented to the V-shaped opening between the flange and the body of the clasp. The fabric is then drawn into the clasp and it passes between the flange and the body thereof into the space 5 until it reaches the point of juncture of the 25 parts. As the fabric is thus drawn in, the separation of the finger from the flange is permitted by a torsional movement of that portion 3 of the metal of the clasp which connects the arm and the main body of the 30 clasp. Inasmuch as only a slight distortion of the connection is necessary to permit the separation of the finger and flange to admit the fabric and as no other part is distorted in such separation, the parallelism of 35 the flange and the locking finger is maintained. Thus the fabric is retained between the flange and the body by reason of the resiliency of the metal of the clasp by a pressure which is uniform throughout the length 40 of the flange insuring a secure holding and avoiding undue pressure on the fabric at any point which might be liable to injure it while secured or during the acts of engaging or disengaging it.

Having thus described my invention, what I claim as new, and desire to secure by Letters Patent, is:—

1. A clasp comprising a body, an arm connected thereto, a slot separating the body 50 and the arm and a flange having one edge thereof connected throughout its length to the

arm and having the other edge overlapping the body, substantially as described.

2. A clasp comprising a body, an arm connected thereto, a slot separating the body 55 and the arm and a flange having one edge thereof connected throughout its length to the arm and having the other edge overlapping the body, and means for securing the fastener in place for use, substantially as 60 described.

3. A clasp comprising a body, an arm connected thereto by a narrow flexible connection, there being a slot between the body and the arm, and a flange having one edge 65 thereof connected throughout its length to the arm and having the other edge overlapping the body, substantially as described.

4. A clasp comprising a body, an arm connected thereto by a flexible connection, 70 the arm tapering from the point of juncture with the connection to its end whereby a tapering opening is formed between the body and the arm, and a flange covering the opening, the flange being attached at one 75 edge throughout its length to the arm and having the other edge overlapping the body, substantially as described.

5. A clasp comprising a body, an arm connected thereto by a flexible connection, 80 the arm being curved on one face and tapering from the connection to its end and a flange attached at one edge throughout its length to the arm and having the other edge 85 overlapping the body, substantially as described.

6. A clasp comprising a body having an upturned edge on one side thereof, an arm connected at one end to the body by a flexible connection and being separated for the 90 greater part of its length from the body by a slot, and a flange overlapping the slot and having one edge thereof connected throughout its length to the arm and having its other edge overlapping the upturned edge 95 of the body, substantially as described.

In testimony whereof I affix my signature in presence of two witnesses.

CHARLES P. EVANS.
